US00D451264B1

(12) **United States Design Patent**
Marvin et al.

(10) Patent No.: **US D451,264 S**
(45) Date of Patent: ** Dec. 4, 2001

(54) **PORTION OF A SHOE SOLE**

(75) Inventors: **William L. Marvin**, Boston; **Neal Kimball**, Framingham, both of MA (US)

(73) Assignee: **Reebok International Ltd.**, Canton, MA (US)

(**) Term: **14 Years**

(21) Appl. No.: **29/111,633**

(22) Filed: **Oct. 1, 1999**

Related U.S. Application Data

(62) Division of application No. 29/086,525, filed on Apr. 15, 1998, now Pat. No. Des. 446,003, which is a division of application No. 29/064,843, filed on Jan. 10, 1997, now Pat. No. Des. 394,937.

(57) **CLAIM**

The ornamental design for a portion of a shoe sole, as shown and described.

DESCRIPTION

FIG. 1 is a bottom plan view of a portion of a shoe sole showing our new design;

FIG. 2 is a left side elevational view thereof;

FIG. 3 is a right side elevational view thereof;

FIG. 4 is a front elevational view thereof;

FIG. 5 is a rear elevational view thereof; and,

FIG. 6 is a perspective view thereof.

The broken line showing of portions of a shoe sole is for illustrative purposes only and forms no part of the claimed design.
